TELEVISION ANTENNA

John Alton McDonald, Los Angeles, Calif.

Application December 29, 1958, Serial No. 53,964

Term of patent 7 years

(Cl. D26—14)

Figure 1 is a front elevational view of a television antenna, showing my new design;

Figure 2 is a top plan view;

Figure 3 is a bottom plan view;

Figure 4 is a rear elevational view; and

Figure 5 is an end elevational view, the opposite end being substantially a mirror image thereof.

I claim:

The ornamental design for a television antenna, substantially as shown and described.
